M. SCOTT.
APPARATUS FOR AND METHOD OF DRAWING CONTINUOUS SHEETS OF GLASS.
APPLICATION FILED, NOV. 24, 1915.

1,204,496.

Patented Nov. 14, 1916.

UNITED STATES PATENT OFFICE.

MARION SCOTT, OF OKMULGEE, OKLAHOMA.

APPARATUS FOR AND METHOD OF DRAWING CONTINUOUS SHEETS OF GLASS.

1,204,496.

Specification of Letters Patent. Patented Nov. 14, 1916.

Application filed November 24, 1915. Serial No. 63,291.

To all whom it may concern:

Be it known that I, MARION SCOTT, a citizen of the United States, residing at Okmulgee, in the county of Okmulgee, State of Oklahoma, have invented certain new and useful Improvements in Apparatus for and Methods of Drawing Continuous Sheets of Glass; and I do hereby declare the following to be a full, clear, and exact description of the invention, such as will enable others skilled in the art to which it appertains to make and use the same.

This invention relates to apparatus for drawing continuous sheets of glass.

The object of the invention is to provide an apparatus of the type named embodying an improved construction whereby a sheet of glass may be drawn from a tank in continuous form and held in upright position above the apparatus as the drawing proceeds without the employment of any support for the sheet.

A further object of the invention is to provide an apparatus of the type named which will be simple in construction and efficient and rapid in operation.

A still further object of the invention is to provide an apparatus in which the sheets of glass will be drawn entirely free of any impurities that may be present in the molten glass in the tank.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a front elevation of a glass drawing apparatus constructed in accordance with the invention; Fig. 2, a side view of same; Fig. 3, a vertical section through a portion of the apparatus, Fig. 4, a transverse section through the apparatus; and Fig. 5, an end view opposite to that shown in Fig. 2.

Referring to the drawings A indicates a glass tank of any desired construction provided with a drawing mouth on its upper side. Mounted upon the tank A is a frame B which includes a rectangular base member 10 surrounding the mouth of the tank. Supported upon the base member 10 adjacent

the ends thereof are inverted U-shaped members 11 and 12. Also mounted on the base 10 adjacent the ends thereof are guides 13 and 14 in each of which are mounted sliding bearings 15 and 16 normally moved toward each other by springs 17. Rotatably mounted in the bearings 15 is an asbestos roller 18, while an asbestos roller 19 is rotatably mounted in the bearings 16, the springs 17 of course serving to press said rollers together. Corresponding trunnions of the rollers 18 and 19 are extended and have fixed thereon respectively gears 20 and 21 disposed in mesh. Mounted on the guide 13 is a bearing 22 in which is rotatably mounted a shaft 23 having fixed thereon a belt wheel 24 and a gear 25, the latter meshing with the gear 21. The shaft 23 is connected with a suitable source of power for effecting the rotation thereof through the medium of a belt 26 engaged over the belt wheel 24. Depending from the arm connecting portion of the members 11 and 12 are arms 27 and 28. Rotatably mounted in bearings 29 carried by the arms 27 are rubber rollers 30 disposed one above the other. It will be noted that the bearings 29 are of the spring pressed slidable type. Likewise there is rotatably mounted in bearings 31 carried by the arm 28 rubber rollers 32. The bearings 31 are also of the sliding spring pressed type and whereby corresponding rollers 30 and 32 are yieldingly forced toward each other. Corresponding trunnions of the rollers 30 are extended and have fixed thereon gears 33 and 34 disposed in mesh with each other. Likewise the rollers 32 have corresponding trunnions extended and fixed on these trunnions are gears 35 and 36 disposed in mesh with each other, the gear 35 also meshing with the gear 34. The gear 36 carries a worm crown 37 which is operatively engaged by a worm 38 rotatably mounted in one of the arms of the member 11 through the medium of a shaft 39. Fixed on this shaft 39 is a beveled gear 40 which meshes with a beveled gear 41 fixed on a shaft 42 rotatably mounted in bearings 43 carried by the member 11. Fixed on the lower end of the shaft 42 is a beveled gear 44 which meshes with a beveled gear 45 fixed on the shaft 23 and whereby the rotation of the shaft 23 will serve to effect not only the proper rotation of the rollers 18 and 19 but also of the rollers 30 and 32. Supported by the frame A and leading to

a point between the rollers 18 and 19 adjacent the ends of the latter respectively are air pipes 46 provided with water jackets 47 for the purpose of maintaining same cool. 5 The delivery ends of these pipes are directed upwardly for a purpose that will presently appear.

To institute the drawing of the glass a length of sheet iron is passed between the 10 rollers 30 and 32 and the rollers 18 and 19 and the machine is then started. It will of course be understood that this length of sheet iron extends into the molten glass. As the rollers move this sheet of iron upwardly 15 the glass has gathered on the lower end thereof and is drawn upwardly with the sheet of iron until only glass is disposed between the rollers 30 and 32 and between the rollers 18 and 19. As the sheet of glass 20 is thus drawn the air passing through the pipe 46 will blow tubular portions 48 at each edge of the sheet of glass and in this way the strength of the sheet is so increased that it will remain perfectly vertical during 25 drawing against any tendency to warp and without the use of any supplemental supports for the drawn portion of the sheet.

It will be noted that the rollers 18 and 19 serve to gather the glass while the rollers 30 and 32 act directly on the sheet of glass 30 to draw same upwardly. In other words the rollers 18 and 19 constitute the gathering rollers while the rollers 30 and 32 constitute the drawing rollers.

What is claimed is:-

1. The combination with a glass tank having a drawing mouth, of a frame supported on the tank around the mouth, a plurality of pairs of drawing rollers mounted in the frame above the mouth, means for rotating said rollers, and means for blowing a tubular edge at each side of the sheet of glass as same is drawn. 35

2. The herein described method of drawing sheet glass consisting of drawing the sheet vertically and simultaneously blowing a tubular portion at each edge of the sheet of glass to prevent warping thereof. 40

In testimony whereof, I affix my signature, in the presence of two witnesses.

MARION SCOTT.

Witnesses:

GEORGE JAMES,
C. E. COVER.
